(57) **CLAIM**

The ornamental design for a telescopic support pole with pivot bar, as shown and described.

DESCRIPTION

FIG. 1 is a front view for a telescopic support pole with pivot bar wherein the pivot bar is in a first configuration, showing our new design;

FIG. 2 is a rear view thereof;

FIG. 3 is a right view thereof;

FIG. 4 is a left view thereof;

FIG. 5 is a perspective view thereof;

FIG. 6 is a perspective view of the telescopic support pole with pivot bar wherein the pivot bar is in a second configuration;

FIG. 7 is a perspective view of the telescopic support pole with pivot bar wherein the pivot bar is in a third configuration;

FIG. 8 is a perspective view of the telescopic support pole with pivot bar wherein the pivot bar is in a fourth configuration; and,

FIG. 9 is a front view of the telescopic support pole with pivot bar wherein the pivot bar is in the first configuration and wherein the support pole is in an extended configuration. The broken lines show portions of the telescopic support pole with pivot bar which form no part of the claimed design.
